UNITED STATES PATENT OFFICE.

WILLIAM Y. MOFFAT, OF SCRANTON, PENNSYLVANIA, ASSIGNOR TO INTERNATIONAL STEAM PUMP COMPANY, A CORPORATION OF NEW JERSEY.

CUT-OFF-VALVE MECHANISM.

1,086,071.

Specification of Letters Patent.

Patented Feb. 3, 1914.

Application filed December 23, 1909. Serial No. 534,681.

To all whom it may concern:

Be it known that I, WILLIAM Y. MOFFAT, a citizen of the United States, residing at Scranton, in the county of Lackawanna and State of Pennsylvania, have invented 5 certain new and useful Improvements in Cut-Off-Valve Mechanisms; and I do hereby declare the following to be a full, clear, and exact description of the invention, such 10 as will enable others skilled in the art to which it appertains to make and use the same.

This invention relates to cut off valve mechanisms for steam pumps, and has for 15 an object to provide improved gear whereby the valves are given a complete opening and are closed to cut off sooner as may be required without effecting the initial opening of the port.

20 A further object of the invention is to provide in a device of the class improved means whereby the valves upon opposite sides of the pump may be simultaneously and similarly adjusted.

25 A further object of the invention is to provide a controlling device of the class adapted to be operated selectively by manual means or automatic devices.

With these and other objects in view, the 30 invention comprises certain novel constructions, combinations and arrangements of parts, as will be hereinafter fully described and claimed.

In the drawings, Figure 1 is a view in 35 elevation of one side of a fragment of a conventional steam pump with the cut off valve applied thereto. Fig. 2 is a view of a similar pump showing the valves in section. Fig. 3 is a top plan view of the form 40 of pump shown at Figs. 1 and 2. Fig. 4 is a slight modification of the apparatus as shown at Figs. 1 to 3 inclusive.

Like characters of reference designate 45 corresponding parts throughout the several parts.

As shown in the drawings the device is applicable to the usual and ordinary pumps, one of which is shown conventionally with the cylinders 10 and piston rod 11, with 50 the usual main valves 12 and the cut off valves 13. The cut off valves 13 are, of course, provided with the usual shafts or stems 14 and with the crank arms 15 in the usual manner.

55 Between the cut off valves 13 a rocker 16 is fulcrumed as at 17 employing the usual

and ordinary fulcrum stud therefor, but the rocker instead of being constructed as usually employed is provided at its upper end with means as the inturned flanges 18 for 60 engaging and maintaining a block 19 slidably therein. The block 19 is provided with a pin 20 upon which are pivoted the links 21 extending in opposite directions to and pivoted at 22 to the extremities of the 65 crank arms 15. The rocker 16 is actuated in the usual manner by means of the link 22' from the crank 23, and it will be apparent that as the rocker 16 is moved the crank arms 15 will also be moved and move there- 70 with the valves 13. It will also be apparent that as the block 19 is moved nearer to or farther from the fulcrum 17, the motion of the valves will be respectively de- 75 creased or increased. To accomplish the adjustment of the block 19 a link 24 is also pivoted upon the pin 20 and its upper end is pivoted to an arm 25 carried upon a 80 shaft 26, which extends transversely across the pump structure, one of the arms 25 being provided at each end of the shaft, that is to say, upon each side of the pump.

For controlling the position of the arm 25, means is provided for moving the shaft 26 rotatably. Such means is shown by the 85 automatic control indicated by the cylinder 27 having a piston 28 mounted therein and pivotally connected with an arm 29 carried rigidly upon the shaft 26 and with a weight 30 tending to normally hold the lever down 90 and the block 19 in the position as indicated at Fig. 1. The cylinder 27 and pis- 95 ton 28, may be of the common form de- 100 scribed in United States Letters Patent No. 312,138 and well known under the name Mason pump governor, the raising of the piston 28, in case of excessive speed, rock- 105 ing shaft 26 through lever 29, so as to raise arms 25 and move blocks 19 upward in rockers 16 for earlier cut-off, this move- 110 ment of the blocks 19 positioning them farther from the rocker fulcrum 17 so as to increase the movement of the cut-off valves and secure the full opening of the ports with earlier cut-off.

The blocks 19 may be adjusted manually, and the engine provided with the automatic control or not, as desired. For the purpose of manual control a hand wheel 31 is provided on shaft 26, this wheel preferably 110 carrying a bolt 32 adapted to engage in the slot 33 of a bracket 34 of the pump frame,

so as to limit the movement of the hand wheel and shaft 26 on their adjustment in either direction. The hand wheel is also preferably provided with a pointer 35 moving adjacent to a graduated scale 36 whereby the position of the block and consequently the adjustment of the valves may be determined by reading from the pointer and scale.

10 It will be apparent that instead of applying the sliding block and guide mechanism to the rocker 16 it may be applied in place of the crank 23 as shown at Fig. 4. In this embodiment the crank is replaced by the 15 flanged arm 37 with the block 38 slideable therein and controlled by the link 24', which link is in turn controlled similarly to the link 24. The block 38 is connected with the rocker by means of the link 22', the rocker 16' being of the usual type ordinarily employed upon such structures.

10 It will be apparent that the movement of the sliding block 38 in the guide arm 37 will accomplish nearly the same result as 25 the movement of the block 19 in the guide 18. It is found, however, that by the use of the structure shown at Fig. 1 better results are attained in that the valves are at 30 all times given the full initial opening and only the closing effected by the adjustment.

Considering now the central position of the rocker 16 and the crank arms 15, it is to be noted that the parts are so located and arranged that the links 21 make a relatively 35 flat angle with the horizontal, in the various positions to which they may be adjusted in actual practice. Therefore, during the adjustment of the sliding block in or out from the fulcrum 17, the cut-off valve itself 40 will be but very slightly shifted or displaced relative to its port, the amount of such displacement being proportional to the difference of the versed sines of the angles of the links before and after the change, 45 whereas the relation of the amount of movement of the valve, after a change of the adjustment, to the amount of its movement prior to the change, is proportional to the difference in the sines of the angles of the 50 links before and after the change. Since with flat angles the rate of change of the sine is very great, compared with the rate of change of its versed sine, it is clear that by applicant's arrangement a material change 55 of the amount of movement of the valve may be made by shifting the pivotal connection 20 of the links in or out on the rocker, without substantial displacement of the cut-off valve from its normal initial position relative to the port. Consequently, the said 60 cut-off valve may always allow its port to remain fully open at the initial position of the valve, notwithstanding the adjustment

of the pivotal point of connection of the links to the rocker.

It will be observed that the movement illustrated in Fig. 1 is particularly advantageous because the ports are so arranged that the point of connection 20 of the links to the sliding block 19 may be adjusted, not 70 only above but also below the horizontal plane through the connections 22 of the links and crank arms 15. Thus, as will be seen from said Fig. 1, the point of connection 20 may be shifted from a point lying a certain distance below the horizontal plane through the points 22 to a position lying an equal distance above said horizontal plane, and in both of said positions the cut-off valves will be in identical positions relative 80 to the ports, yet the amount of movement of the valves will be materially different. Therefore, since a greater amount of movement of the cut-off valve implies a greater speed of movement, it follows that with such 85 greater movement the valve, traveling from its initial position where the port is wide open, will close said port sooner than it will when having a smaller amount of movement, and consequently a relatively slower speed. 90

What I claim is:—

1. In a cut-off valve mechanism, rocking cut-off valves, a rocker pivoted between the valves, arms connecting the rocker with the valves, and means for actuating the valves 95 through the rocker including a member adjustable for varying the point of cut-off and arranged so that the movement of the valves is increased on adjustment of said member for earlier cut-off.

2. In a cut-off valve mechanism, rocking cut-off valves, a rocker pivoted between the valves, a member adjustable longitudinally upon the rocker, arms connecting the adjustable member with the valves in such a 105 manner that the movement of the valves is increased on adjustment of the member for earlier cut-off, and means for operating the rocker.

3. In a cut-off valve mechanism, rocking 110 cut-off valves, levers extending from the valve stems, a rocker pivoted between the valves, a member adjustable upon the rocker toward its fulcrum for later cut-off and away from its fulcrum for earlier cut-off, 115 and arms pivoted to the fulcrum and to the levers and arranged to increase the throw of the levers when the adjustable member is adjusted for earlier cut-off.

In testimony whereof I affix my signature 120 in presence of two witnesses.

WILLIAM Y. MOFFAT.
